UNITED STATES PATENT OFFICE.

RICHARD S. CARTY, OF DETROIT, MICHIGAN, ASSIGNOR OF ONE-HALF TO CHARLES B. ROBINSON, OF DETROIT, MICHIGAN.

DEVICE FOR DISPLAYING AUTOMOBILE NUMBERS.

Application filed January 10, 1927. Serial No. 160,128.

My invention relates to displaying the distinguishing number of an automobile and an object of my improvement is to provide for the destruction of the sheet bearing the number by any unauthorized interference therewith.

I secure this object in the device illustrated in the accompanying drawings, in which:—

Figure 1 is a perspective view of an apparatus embodying my invention, partly broken away.

Figure 2 is a front sectional elevation. The front of the casing being removed to exhibit the interior construction, the section being in approximately the plane II, II Figures 1 and 3.

Figure 3 is a section on the line III, III Figure 2, looking in the direction of the arrows.

Figure 4 is a section on the line IV, IV Figure 2, looking in the direction of the arrows.

Figure 5 is a detached view of the sheet bearing the number.

Figure 6 is a front elevation to a reduced scale, partly broken away of the entire apparatus.

Figure 7 is a plan view of the disengaging rod, and

Figure 8 is an elevation of the same, looking from below Figure 7.

1 is an enclosed casing having a compartment 2 and an upper compartment 3 separated from the first named compartment by a glass partition 4. 5 is a cover hinged at its upper edge at 6 to the casing 1 and adapted to close the otherwise open front of the compartment 3. 7 is a glass plate closing the otherwise open front of the compartment 2. 9 is a slot in one end of the casing 1 through which the glass plate 7 may be introduced, its inner edge engaging in a slot 9^a in the opposite end wall of the casing 1. 8 is a cover screwed upon the end wall of the casing 1 to cover the slot 9. 10, 10 (Fig. 2) are lamps in the compartment 3.

11, 11 are supporting end plates extending parallel to each other and to the end walls of the casing 1 and adjacent to said walls. 17 is a sectional rod having a turn-

buckle 17^a and extending between the plates 11, 11. 12 is a roller pivoted at its ends in the plates 11, 11, and provided with attaching pins 12^a, 12^a. 13 is a roller pivoted at its ends in the lower portion of the plates 11, 11, entirely similar to the roller 12 pivoted towards the upper ends of said plates. 13^a, 13^a are attaching pins extending from the roller 13. 12^b is a squared extension of the shaft of the roller 12 and 13^b is a similar extension of the shaft of the roller 13. 16^b, 16^b (Fig. 1) are holes in the end wall of the casing 1 through which a key may be passed to engage the squared extension 12^b or 13^b to rotate the rollers 12 or 13. 14, 14 are ratchet wheels upon the shaft of the roller 12 outside of and adjacent to the plate 11. 15, 15 are similar ratchet wheels on the ends of the shaft of the roller 13. 14^a is a pawl adapted to engage the teeth of the ratchet wheel 14. There is a pawl 14^a engaging each of the ratchet wheels 14 and between the pawls extends a rod 14^b by which said pawls may be simultaneously raised to disengage this from the teeth of 75 the ratchet wheels 14, 14. There is a pawl 15^a adapted to engage the teeth of each of the ratchet wheels 15, 15.

The number of the automobile is placed upon a sheet of paper or other suitable material of the shape shown in Figure 5, in which 16 denotes the number sheet and 16^a the engaging apertures in the upper and lower portion of said sheet. Said engaging apertures are placed over the pins 12^a and 13^a and the rollers 12 and 13 turned in opposite direction until the sheet is drawn taut and is held, as shown in Figure 4, converging outwardly from the top to its lower portions and in front of the glass plate 7 so that the number may be seen through said plate and will be illuminated by the light from the lamps 10, 10 in the upper compartment 3.

18 is a rotatable shaft pivoted at its ends in the plates 11, 11 and located between the rollers 12 and 13 and parallel thereto. 20, 20 are ratchet wheels on the axle of the shaft 18 and 21, 21 are pawls engaging the teeth of the ratchet wheels 20, 20. 19, 19 are spiral springs adapted to rotate the shaft 18. 18^c 100

is a squared shaft which may be engaged by a key passing through the hole 18^b in the end of the casing 1, to wind up the springs 19, 19, which springs are held in their wound up condition by the pawls 21, 21 engaging the ratchet wheels 20, 20 and when said pawls are released the said springs unwind, rapidly rotating the shaft 18. 18^a is a series of cutter bars extending at right angles, or radially, from the shaft 18 and arranged in a spiral extending about half way around the shaft. The shaft 18 is arranged, as shown in Figure 4, so that the sheet number 16 will clear it but the bars 18^a will strike against and cut said sheet into strips and destroy the number thereon when the shaft 18 is rotated.

23, 23 are tubular guides extending vertically and secured to the bottom of the casing 1 inside and towards the ends of said casing. 25, 25 are tubular parts fitting over and adapted to slide on the guide 23 and preferably having their upper ends closed. 24, 24 are helical springs in the guides 23, 23 acting to force the parts 25, 25 upward when said parts are free to move. 25^a, 25^a are horizontal extensions from the lower ends of the parts 25, 25.

26 is a rod extending horizontally between the plates 11, 11 and adapted to reciprocate backward and forward in slots 27 in said plates. 26^a is a rod extending horizontally forward from the center of the rod 26 and passing outward through an aperture in the front of the casing 1. 26^b is a roller adjustably supported below the rod 26 and rigidly secured to said rod. There is a roller 26^b at each end of the rod 26, when the rod 26 is pulled forward the rollers 26^b come over the extensions 26^a of the parts 25 and hold said parts in their lowest position with the springs 24 contracted. When said rod is pushed backward, as indicated in broken lines in Figure 4, the rollers 26^b are removed from over the extensions 25^a and the parts 25 are free to move upward under the impulse of the springs 24 unless otherwise restrained.

22, 22 are rods extending vertically downward, pivoted at their upper ends to the pawls 21, 21 and extending at 22^a over the extensions 25^a of the movable parts 25.

The glass 7 is cut away at 7^a, 7^a (Fig. 6) so that if said glass is moved endwise until such cut away parts come over the parts 25 the last named parts will be freed from the restraint of the glass 7 resting upon their upper edges and permitted to rise under the impulse of their springs 24, 24.

33, 33 are tubular guides extending from the rear wall of the casing 1 and having helical springs 31, 31 therein. 28 is a bolt having a head 30. The shank of the bolt 28 passes through the spiral spring 31 and through the guide 33 and through an aper-

ture in the rear wall of the casing 1 and at this point has its threads engaged by a nut 29. The nut 29 is screwed up to contract the spring 31 and secure the casing 1 to a support 29^a. 32, 32 are rods extending laterally and horizontally from the heads 30 of the bolts 28 and provided at their outer ends with rollers 34 adapted to reciprocate in slots in the plates 11, 11.

The operation of the above described apparatus is as follows:

The parts 25 are forced downward and are engaging rod 26 is drawn forward so as to hold the parts 25 in their lower positions and the springs 19, 19 are wound up, 80 the shaft 18 being in the position shown in Figure 4. The sheet 16 is now engaged by the aperture 16^a over the pins 12^a, 12^a and 13^a, 13^a and the rollers 12 and 13 are turned to tighten said sheet. The casing is attached 85 to a convenient support by the bolts 28 and said bolts are drawn up to considerably contract the spring 31 and even so that the head 30 of the bolt shall engage the end of the guide 33, thus holding the casing in position to show the number through the open front of the casing. The glass 7 is now slid inward through the opening 9 and rests with its lower edge upon the parts 25, 25. The engaging rod 26 is now pressed inward 95 by means of the rod 26^a until the rollers 26^b are free of the parts 25^a and the rod 26^a falls inside the casing. The aperture 9 is closed by securing the covering plate 8 thereon.

Now should anyone attempt to remove the number sheet he might take off the cover plate 8 and draw the glass 7 outward in the slot 9. If this were done, when the cut away portions 7^a, 7^a came over the parts 25, 105 25 said parts would be forced upward, the extensions 25^a would engage the lower ends of the rods 22 and force the pawls 21, 21 out of engagement with the teeth of the ratchet wheels 20, 20 releasing the shaft 18, 110 which would be rapidly rotated by the springs 19, 19 thus by means of the bars 18^a cutting the sheet 16 into shreds and destroying said sheet and the number thereon. Should the plate 7 be broken and removed 115 of course the same result would follow.

Should an attempt be made to remove the casing 1 entirely by unscrewing the nuts 29 or cutting the bolts 28 said bolts would be released and the springs 31 would force them forward carrying the rollers 35 into contact with the pawls 21 releasing the shaft 18, as before described, and destroying the number sheet.

What I claim is:

1. In an apparatus of the kind described, the combination of a sheet bearing a number and an automatic means actuated by stored power for destroying the material bearing said number.

2. In an apparatus of the kind described, the combination of a sheet bearing a number and an automatic means actuated by stored power for destroying the material bearing

5 said number and means for tripping said automatic means adapted to be actuated by unauthorized interference therewith.

3. In an apparatus of the kind described, the combination of a sheet bearing a number, a shaft pivoted adjacent to said sheet, automatic means actuated by stored power for rotating said shaft and means whereby the rotation of said shaft shall destroy the material bearing said number when said

15 shaft is rotated.

4. In an apparatus of the kind described, the combination of a sheet bearing a number, a shaft pivoted adjacent to said sheet, automatic means for rotating said shaft and 20 bars arranged in a helical series about said bar and adapted to destroy the material bearing said number when said shaft is rotated.

5. In an apparatus of the kind described, the combination of a destructible sheet, a rotatable bar pivoted adjacent to said sheet, means whereby the movement of said bar shall destroy said sheet, a spring adapted to move said bar to destroy said sheet, a 25 releasable means for restraining said bar from movement and means whereby said restraining means shall be released by unauthorized interference.

6. In an apparatus of the kind described, 30 a sheet bearing a number, a rotatable shaft pivoted adjacent to said sheet, means whereby the rotation of said shaft shall destroy said sheet, a spring acting to revolve said shaft, a ratchet wheel on said shaft, a pawl coacting with said ratchet wheel to restrain 35 said bar from rotation and means for tripping said pawl for the purpose described.

7. In an apparatus of the kind described, a sheet bearing a number, a rotatable shaft 40 pivoted adjacent to said sheet, means whereby the rotation of said shaft shall destroy said sheet, a spring acting to revolve said shaft, a ratchet wheel on said shaft, a pawl coacting with said ratchet wheel to restrain 45 said bar from rotation and means for tripping said pawl, a casing enclosing said sheet and a spring pressed member held in position in which the spring is stressed by a portion of said casing, said member being 50 adapted to actuate said tripping means when 55 released for the purpose described.

8. In an apparatus of the kind described, a sheet bearing a number, a rotatable shaft 55 pivoted adjacent to said sheet, means whereby the rotation of said shaft shall destroy said sheet, a spring acting to revolve said shaft, a ratchet wheel on said shaft, a pawl coacting with said ratchet wheel to restrain 60 said bar from rotation and means for tripping said pawl, a casing, a spring pressed

member securing said casing to a support and means whereby said securing means shall operate said tripping means when released for the purpose described.

9. The combination of a casing having a 70 glass front, a sheet within said casing bearing a number that may be seen through said glass, automatic means for destroying said number, a member adapted to travel in a vertical path, a spring tending to raise said 75 member, said glass resting upon said member to hold it in position against the action of said spring and a tripping means for said automatic means, said member being adapted to actuate said tripping means when 80 released.

10. The combination of a casing having a glass front, a sheet within said casing bearing a number that may be seen through said glass, automatic means for destroying said 85 number, a member adapted to travel in a vertical path, a spring tending to raise said member, said glass resting upon said member to hold it in position against the action of said spring and a tripping means for said 90 automatic means, said member being adapted to actuate said tripping means when released, said glass being capable of lateral displacement and being cut away at its edge 95 so as to release said member when so displaced.

11. The combination of a casing having a glass front, a sheet within said casing bearing a number that may be seen through said 100 glass, automatic means for destroying said number, a member adapted to travel in a vertical path, a spring tending to raise said member, said glass resting upon said member to hold it in position against the action of said spring and a tripping means for 105 said automatic means, said member being adapted to actuate said tripping means when released and a restraining means for holding said member in the position with the spring contracted when said glass is not in place, 110 said restraining means being adapted to be permanently removed from operative position.

12. In an apparatus of the kind described, the combination of a casing, a sheet bearing 115 a number thereon supported by said casing, automatic means for destroying the material bearing said number, means for attaching said casing to an automobile and means whereby the releasing of said attaching 120 means shall release said automatic means to destroy said number.

13. In an apparatus of the kind described, the combination of a casing, a sheet bearing 125 a number thereon supported by said casing, automatic means for destroying the material bearing said number, said casing having a glass wall, and means whereby the removal of the glass shall release said automatic means to destroy said number.

14. In an apparatus of the kind described, the combination of a casing, a sheet bearing a number thereon an automatic apparatus therein adapted to destroy said number, a
5 spring impelled part 25 adapted to trip said automatic apparatus when released, a glass plate acting to hold said part against the

action of said spring and means operable from outside of said casing for holding said part against the action of said spring and releasing the same for the purpose described. 10

In testimony whereof, I sign this specification.

RICHARD S. CARTY.
